UNITED STATES PATENT OFFICE

FREDERICK BREDEL, OF ST. LOUIS, MISSOURI, ASSIGNOR OF THIRTY ONE-HUNDREDTHS
TO THOMAS D. MILLER, OF ST. LOUIS, MISSOURI; LEE W. GRANT ADMINISTRATOR OF
SAID FREDERICK BREDEL, DECEASED

PROCESS OF HEATING MUFFLES, RETORTS, AND THE LIKE

Application filed May 9, 1930. Serial No. 450,892.

This invention relates to systems for heating muffles, retorts, and the like. Heretofore it has been difficult to evenly heat such retorts and muffles, especially vertical or horizontal coke ovens, throughout their entire length or height. To more evenly heat vertical ovens throughout the entire horizontal plane, and horizontal ovens throughout their entire vertical plane, I have devised a system of heating wherein a secondary (regulated) combustion takes place after the products of combustion have arrived at the end opposite to the place where the first combustion took place. This secondary combustion takes place at what is generally called the front of vertical ovens and at the top of horizontal ovens, thereby equalizing the heating of said ovens by securing a combustion at opposite horizontal points in vertical ovens, and at opposite vertical points in horizontal ovens.

To obtain this double combustion, I heat the ovens by one or more units of three flues each. Two of such flues being heated by a primary and one by a secondary combustion. If deemed advisable, this secondary combustion heating flue can be split up to form two or more flues in which case each unit would consist of two flues for primary and two or more flues for secondary combustion. The combustion chamber for each primary combustion flue is supplied with an over rich mixture of fuel gas and air, that is an excess of combustible gas and an insufficient air supply; and the other primary combustion chamber is supplied with a lean mixture of gas and air, that is an excess of air and an insufficient supply of combustible gas. When the products of the partial combustion flues meet the products of the flue having an excess of air, at their return passage, a secondary (complete) combustion takes place and in this way each of the three flues is evenly heated by regulating the amount of gas and air supplied to the two primary combustion flues.

The number of units required to heat vertical and horizontal ovens will depend on the height of the vertical oven or the length of the horizontal oven. The products of com-

bustion when leaving the secondary combustion flue or flues can go either directly to the chimney (which, however is not advisable) or they can be used to preheat either the air or gas required for heating the ovens, or for heating both air and gas as shown in the drawings. The latter arrangement is preferable when using so-called producer or other gas of low heating value.

In the accompanying drawings, which form part of this specification and wherein like symbols refer to like parts wherever they occur,

Fig. 1 is a vertical cross-section through a vertical coke oven embodying my invention, the section being taken on the line 1—1 in Fig. 4.

Fig. 2 is a horizontal cross-section on the line 2—2 in Fig. 1.

Fig. 3 is a vertical cross-section through said oven on the line 3—3 in Fig. 4.

Fig. 4 is a horizontal cross-section through said oven, the upper and lower halves of said section being taken on the lines 4—4 and 4a—4a, respectively, in Fig. 3.

Fig. 5 is a vertical cross-section of a horizontal coke oven embodying my invention, the left and right halves of said section being taken on the lines 5—5 and 5a—5a, respectively, in Fig. 6; and

Fig. 6 is a partial longitudinal section through the horizontal coke oven on the line 6—6 in Fig. 5.

Flues 7, 8, 9 and 10 (see Figs. 2, 3 and 4) are air flues of a vertical coke oven. I—7, I—8, I—9 and I—10 (see Figs. 3 and 4) indicate air inlets for the air flues 7, 8, 9 and 10 and are fitted with suitable air admission regulating valves designated by single-feathered arrows (see Fig. 4). Flues 11, 12, 13 and 14 (see Figs. 2, 3 and 4) are fuel-gas flues. I—11, I—12, I—13 and I—14 (see Fig. 4) indicate fuel-gas inlets fitted with suitable gas admission valves designated by double feathered arrows (see Fig. 4). I—15 and I—16 (see Figs. 1 and 4) indicate primary combustion chambers where the air and fuel-gas meet. 15a and 16a (see Figs. 1 and 4) indicate primary heating flues for heating part of retorts 19 (see Figs. 2, 3 and 4).

(see Figs. 1 and 2) indicate secondary combustion chambers where gases from flues 15a and 16a meet and then enter into secondary heating flues 18 (see Figs. 1 and 2) thereby heating the rest of the retort 19. The gases from flues 18 enter the recuperator 20 (see Figs. 1, 2 and 4) by means of connecting flues 18a (see Figs. 1 and 2) and ultimately leave the recuperator by means of flues 20a (see Figs. 1 and 3) which lead to the atmosphere.

The horizontal coke oven shown in Figs. 5 and 6 is provided with air inlets I—21, I—22, I—23, I—24, I—25 and I—26 (see Fig. 5) which correspond to the inlets I—7, I—8, I—9 and I—10 of Figs. 3 and 4. Air flues 21 to 26 (see Figs. 5 and 6) correspond to air flues 7 to 10 of Figs. 2, 3 and 4. Gas inlet flues I—27 to I—32 (see Fig. 5) correspond to gas inlet flues I—11 (see Fig. 4); and gas flues 27 (see Fig. 5) correspond to gas flues 11 to 14 (see Figs. 2, 3 and 4).

Primary combustion chambers 33 and 34 (see Figs. 5 and 6) correspond to primary combustion chambers 15 and 16 (see Figs. 1 and 4). Primary heating flues 33a and 34a (see Figs. 5 and 6) correspond to primary heating flues 15a and 16a (see Figs. 1 and 4). Secondary combustion chambers 35 (see Figs. 5 and 6) correspond to secondary combustion chambers 17 (see Figs. 1 and 2). Secondary heating flues 36 (see Figs. 5 and 6) correspond to secondary heating flues 18 (see Figs. 1 and 2). Connecting flues 36a (see Figs. 5 and 6) correspond to connecting flues 18a (see Figs. 1 and 2). Recuperators 37 (see Figs. 5 and 6) correspond to recuperators 20 (see Figs. 1, 2 and 3). Outlet flues 37a (see Figs. 5 and 6) correspond to outlet flues 20a (see Figs. 1 and 3). The retorts or ovens 38 (see Fig. 5) correspond to retorts 19 (see Figs. 2, 3 and 4).

The following is a description of the operation of the above heating system for each individual unit consisting of two primary flues and one or more (one only shown) secondary combustion flues. Air and gas in correct proportion to form complete combustion without excess of oxygen is admitted to flues 7 and 8, 11 and 12, such air and gas being regulated preferably by valves at the inlets to said flues, until the right heat is obtained. Most of the heat will be absorbed while passing through flues 15a and 16a, and heating flue 18 will be found to be too cold. An extra amount of fuel-gas is now admitted to flues 11 by means of valve at I—11, and also an extra amount of air to flue 8. This will not materially change the temperature in flues 15a and 16a, but the unconsumed gas, when leaving the flue 16a and meeting the surplus air from flue 15a in secondary combustion chamber 17, will cause a secondary combustion to supply the necessary extra heat. To heat flues 18 properly, it is only necessary to so adjust entrance air and gas valves of flues

7 and 8; and 11 and 12, respectively. So far as the flue 18 is concerned, it is immaterial if flue 15a or 16a has a surplus of fuel-gas.

By the above it will be seen that the heat in any part of the above heating system is under perfect control. If desired, the secondary combustion flue may be split up so as to consist of two or more secondary combustion flues to act tandem the same as one flue.

What I claim is:

1. The improvement in the process of heating a muffle or retort having two primary combustion flues and one secondary combustion flue contiguous to the walls thereof for heating the same, with the primary combustion flues arranged to discharge into the secondary combustion flues, which improvement comprises continuously burning in one of said primary combustion flues a fuel gas with insufficient air for complete combustion of the fuel gas, separately burning in the other of said primary combustion flues a second portion of fuel gas with an excess of air over that required for the complete combustion of the second portion of fuel gas and then passing the gases from the combustions of the two portions of fuel gas from said primary combustion flues into said secondary combustion flue and combining the gases therein and continuing the combustion in said secondary combustion flue and conveying heat to said muffle or retort from each of the three combustion flues.

2. The process of heating a muffle or retort which comprises burning in one zone a fuel gas with insufficient air for complete combustion of the fuel gas, separately burning in another zone a second portion of fuel gas with an excess of air over that required for complete combustion of the second portion of fuel gas, combining the gases from the combustions of the two portions of fuel gas and continuing the combustion of the unburned fuel gas in a third zone separate from the two mentioned zones and separately conveying heat to said muffle or retort from the combustion zone of each of the three combustion steps.

Signed at St. Louis, Missouri, this 2nd day of May, 1930.

FREDERICK BREDEL.
